REVERSIBLE DOUBLE ENDED FUSE PLUG

William J. Luse, New York, N. Y.

Application December 18, 1929
Serial No. 414,984

17 Claims. (Cl. 200—125)

This invention is a reversible double ended screw fuse plug adapted to be used twice, and the primary object of the invention is to provide an unusually simple, economical and efficient construction of this character which will embody, among other features, means to indicate when one end of the fuse has been blown, means to indicate amperage for which the particular fuse is to be used, and to so construct the fuse that it will effectually prevent dangerous back flashes which frequently occur in window fuses of the type now in common use.

The invention embodies numerous other features which will be hereinafter more fully explained.

The present invention greatly simplifies manufacturing and assembling of a double ended plug and permits a better plug to be made in a more economical manner than heretofore possible.

In one of its preferred, practical forms, the plug of the present invention comprises a body portion embodying two complementary parts, which, in practice may be of identical structure. They may be molded, pressed or otherwise made of fiber, glass, porcelain, or any other suitable insulating material, and each part is so shaped as to constitute one complete end portion of the plug and one semicircular half of the intermediate portion. When two of those sections are placed in complementary relation, they are adapted to be secured together by merely screwing on to the opposite ends of the plug the usual metallic screw sleeves. The cooperating sections of the plug may be provided with semicircular channels adapted to collectively register to provide an interior circumferential channel adapted to hold a partition in place so as to divide the interior of the plug into two distinct chambers in each of which the fuse element is positioned.

The fuse elements are associated with the plug in a novel manner as will hereinafter be more fully explained and they are carried from the interior of the plug through the side wall thereof and into a position at one end of the corresponding shell where they are secured to the shell by a drop of solder which is adapted to be positioned within a recess in the plug in such manner as to form a key between the shell and the plug and thereby lock the shell against unscrewing. Semicircular openings are provided in the joining lines of the respective sections, so that when the sections are assembled, these semicircular openings will register to form circular openings for venting or for tell-tale purposes.

Another feature of the invention consists in carrying the fuse element from the interior of the plug through an opening in the side wall thereof beneath the metal sleeve and venting through this opening so as to utilize the sleeve as a sort of muffler to dissipate the force of gases generated during blowing of the fuse before they are discharged into the outer atmosphere.

Another feature of the invention resides in the provision of a cap adapted to screw on to that end of the fuse plug which is not in use as a fuse, said cap serving to cover and conceal said end of the plug.

Features of the invention, other than those specified, will be apparent from the hereinafter detailed description and claims, when read in conjunction with the accompanying drawing.

The accompanying drawing shows one practical embodiment of the invention, but the construction therein shown is to be understood as illustrative, only, and not as defining the limits of the invention.

Figure 1 is a perspective view of one fuse section.

Figure 2 is a side elevation of the fuse of this invention showing one section in full lines, the opposing section in dotted lines and one metal sleeve in section.

Figure 3 is a longitudinal central section through the plug.

Figure 4 is a transverse section on the line 4—4 of Figure 3.

Figure 5 shows the plug cap, partly in central section and partly in elevation.

Figure 6 shows one half of a modified form of plug body in central section.

The plug of this invention embodies two sections which are preferably of identical form, so that they may be made in a single mold, all alike, and any two assembled to form a complete plug. Each section embodies a semicylindrical tubular portion 1 on one end of which is formed an integral cylindrical portion 2 provided on its outer side with a somewhat smaller substantially semispherical domed end 3. All parts of this section are formed so that they will readily "draw" from a mold and for this reason the inner end 4 of the cylindrical portion 2 is flat throughout, but is provided with an axial passage 5 through which the fuse element may be passed.

The semicylindrical part 1 is provided intermediate its ends with an enlarged flange 6 which may be semicylindrical as shown or may be semi-hexagonal. In practice, the cylindrical flange

may be used on fuse plugs of over 15 amperes, while the same hexagonal flange may be employed to denote fuses of 15 amperes or under, although other means for indicating amperage 5 may be employed.

The outer or peripheral face of the flange 6 may be knurled or otherwise roughened, so as to better function as a finger piece for screwing in or removing the fuse plug, if the flange is 10 hexagonal, knurling is not necessary.

Each section 1 is shown as provided intermediate its ends with a semicircular channel 7 to receive a part of a partition 8 having a perforation 22. However, if desired, the partition 8 15 may be molded in semi-circular halves which are integral with the respective section as shown in Figure 6. In this latter case, the perforation in said partition can be cast one half in each part so as to register to form the perforation 20 when the parts are brought together.

Semicylindrical passages 9 are cast in the edge of the part 1 and an open sided notch 10 is also preferably molded in the end of the part 1. A pocket or depression 11 is molded in the dome 25 3 adjacent the shoulder 12 on the base of this dome.

The fuse element, designated 14, is adapted to be passed through the passage 5 in the cylindrical part and is secured therein by a split 30 rivet 15 as shown best in Figs. 1 to 3. The head of the rivet bears against a short projecting portion of the fuse element at the outer end of the dome 3 while the inner end of the rivet is bent outwardly to clamp the parts firmly in 35 place. The fuse element is looped, as shown and extends over the edge of each cylindrical part 4, as shown in Figs. 1 and 3. The free edge left extending while two sections of the character shown in Fig. 1 are placed in complementary relations as indicated in Fig. 2. If 40 the separate partition 8 is to be used, it is slipped into place before the two sections are assembled. After assembly, the metal sleeves 16 are passed 45 over the opposite ends of the sections and ridges or projections 17 formed upon said sections act as threads on which the sleeves may be screwed until the flanges 18 at the outer ends of the sleeves abut the shoulder 12 as shown in Figure 5. If a separate circular partition is fitted into 50 the semi-circular channels, as shown, this partition acts as a key to lock the sections against relative longitudinal shifting.

It will be noted that the fuse elements 14 pass from the interior of the fuse through openings 10 which are positioned beneath the sleeves 16. These fuse elements may be carried along the plug to either the inner or outer ends of the sleeves as may be desired. If carried to the outer end of the corresponding sleeve, the fuse 60 element is secured to the sleeve by means of a drop of solder indicated at 23 so formed as to extend into the pocket 11 and form a key to lock the sleeve against rotation. A similar pocket 11a may also be formed in each plug section adjacent the inner end of each sleeve, and a drop of solder 23a introduced thereinto 65 and attached to the sleeve to form an additional key at this point. If the fuse element is carried to the inner end of the sleeve it may be secured 70 to the sleeve by this drop of solder 23a. When the sleeves are in place as stated, they will clamp the sections of the plug firmly together and will preclude movement of such sections in all directions. Furthermore, the solder keys 23 or 23a will firmly lock the sleeves against 75 rota-

tion on the sections and make the assembly a permanent one.

If desired, the inner end of each sleeve may be flanged over or spun into an annular channel 80 20 formed on the outside of the sections as shown at 19 in Fig. 3, but this is optional. If the end of the sleeve is spun into the channel, it will clamp the fuse element sufficiently tight to obviate the necessity of soldering said element to the sleeve.

It will of course be understood that when the two sections are assembled the semi-circular openings 9 will register to form cylindrical openings which may be used for venting purposes. Into one or more of these openings on either side of the partition may be introduced mica disks 21 to act as tell-tales for the purpose of showing when the fuse has blown, for when the fuse blows, it will cloud or smoke a piece of mica to clearly show that the fuse has blown. Venting of the interior of the plug is had through such of these opening as are not sealed by the mica as well as through the openings 10 through which the fuse elements preferably extend. These openings 10 are covered by the sleeve so that as the gases blow through the openings, they are discharged into the interior of the sleeves in which their force is spent with a muffling effect. The space between the sleeves and the plug sections which they embrace will 105 operate as a muffling space and there is sufficient leakage about the ends of the sleeves to permit escape of the gases. One or more pockets 11a 100 may be provided to permit the escape of these gases.

In practice, I preferably color one end of the plug and leave the other end of the plug in its natural state. In use, the colored end is used first, so that if a person sees the colored end 110 showing outside of the fuse plug socket, he will know that the plug cannot be turned around as the outer end has already blown.

In Figure 5, I have shown a cap of insulating material provided on its interior with threads and of a size to permit these threads to screw over either end of the plug. The purpose of this cap is to cover and conceal the end of the plug which is not introduced into the socket of the fuse box, in order that the design of the end of the fuse plug cap will harmonize with the 120 standard single plugs in appearance, especially where uniformity and neatness are desired, in glass cabinets, etc. In any event the use of the cap may be eliminated, and in the event the cap cover is used, a special color or other identification may indicate amperage.

The plug of this invention is of unusually simple construction. It may be economically manufactured and is thoroughly efficient in its operations. It has a relatively large explosion 135 chamber at either side of the partition and the perforation of the partition allows explosive gases within either chamber of the plug, to escape into the other chamber without the risk of blowing the fuse in the latter chamber. The 140 arrangement of the parts is such that flash backs, such as commonly occur in the well known single fuses now in use which embody mica windows, will not occur with the fuse of the present invention because there is adequate provision for the escape of explosive gases coupled with solid fuse plug end. Furthermore, the sleeves lock the sections of the plug together and are thus locked to the sections in a manner to absolutely preclude the unscrewing of the 145 150

sleeves, both by the spinning in of the inner ends of the sleeves into the channels of the plug sections and by the solder keys 23 and 23a which I have described. With this plug, the attempt to unscrew a plug from a socket cannot possibly result in the loosening of the sleeve from the plug as so commonly occurs in fuse plugs as now constructed. On the contrary, the arrangement is such that the sleeves cannot possibly become disengaged from the fuse sections.

I call attention to the marked simplicity with which the fuse elements are secured at the end of the plug sections. An ordinary split rivet not only serves to accomplish this result, but the head of the rivet functions as the end contact of the plug and has a good electrical connection with the fuse element. This fuse element may in practice be of any suitable character such as wire or strip fuse material, and it may be weakened as by flattening it or perforating it as shown at 24 in Fig. 1, so that when it blows it will be ruptured at this point.

The amperage may be identified, in addition to the manner already described by having the center peripheral flange 6 colored on both sides to denote under or over a certain amperage of the fuse plug, or the ends of the plug may be colored to denote the individual amperage of each plug.

When using the ends of fuse plug to denote amperage, I employ in lieu of the one colored end which indicates when this end has been used on the fuse plug, another means of coloring only one side of the peripheral flange 6 which answers the same purpose, as the one colored end of fuse plug when used or blown.

The advantages are that the operator becomes better acquainted with the fuse plug problem, in that he may instantly determine the proper ampere fuse to use by noting the colors on plug ends. He can also readily determine when one end of the fuse plug has already been used. This indicating means on the fuse plugs is very important, as without this indication, one is placed at a great disadvantage, in many ways. Delay, worry, difficulty and negligence is thus eliminated to a great extent by the said means of not only indicating the proper fuse plug to use, but also denoting when one end of the fuse plug has been used.

It will be apparent from the foregoing detailed description that the fuse plug of this invention embodies several novel features some of which in practice may be employed without necessarily employing all of them. Furthermore, structural details may be modified without departing from this invention. For these reasons, the invention is not to be understood as restricted to the exact construction illustrated, but is to be construed as fully commensurate with the appended claims.

Having thus fully described the invention, what I claim as new and desire to secure by Letters Patent is:

1. A double ended fuse plug comprising a pair of complementary semicylindrical sections adapted to be placed in edge abutting relation to form a cylindrical plug body, one end of each of said semicylindrical sections being provided with an integral circular end piece adapted to serve as a closure for the opposite ends of the cylindrical body when said sections are assembled, said sections being provided interiorly with circumferential channels adapted to register when the sec-

tions are assembled and a partition peripherally engaging said channels and held in place thereby, said partition serving to lock the sections against relative longitudinal movement.

2. A double ended fuse plug comprising a pair of complementary semicylindrical sections adapted to be placed in edge abutting relation to form a cylindrical plug body, one end of each of said semicylindrical sections being provided with an integral circular end piece adapted to serve as a closure for the opposite ends of the cylindrical body when said sections are assembled, and threaded metallic sleeves embracing the opposite end portions of the cylindrical body to secure said sections together, said sleeves being exteriorly threaded to screw into a fuse socket.

3. A double ended fuse plug comprising a pair of complementary semicylindrical sections adapted to be placed in edge abutting relation to form a cylindrical plug body, one end of each of said semicylindrical sections being provided with an integral circular end piece adapted to serve as a closure for the opposite ends of the cylindrical body when said sections are assembled, and threaded metallic sleeves embracing the opposite end portions of the cylindrical body to secure said sections together, said sections being provided adjacent one end of each sleeve with a depression, and solder secured to the sleeve and extending into the depression to secure the sleeves against removal from the cylindrical body.

4. A double ended fuse plug comprising a pair of complementary semicylindrical sections adapted to be placed in edge abutting relation to form a cylindrical plug body, one end of each of said semicylindrical sections being provided with an integral circular end piece adapted to serve as a closure for the opposite ends of the cylindrical body when said sections are assembled, threaded metallic sleeves embracing the opposite end portions of the cylindrical body to secure said sections together, said sections being provided adjacent one end of each sleeve with a depression, and solder secured to the sleeve and extending into the depression to secure the sleeves against removal from the cylindrical body, a center contact positioned at the outer end of the circular part of each section, and a fuse element extending from each contact through said circular part into the interior of the cylindrical body and thence to said solder to be secured thereby to the corresponding metallic sleeve.

5. A double ended fuse plug embodying a pair of identical fuse sections of insulating material positioned in complementary relation and forming a complete fuse body closed at both ends, and threaded sleeves embracing the opposite end portions of both sections to maintain them in assembled relation, said sleeves being adapted to screw into a fuse socket.

6. A double ended fuse plug embodying a pair of identical fuse sections of insulating material positioned in complementary relation and forming a complete fuse body closed at both ends, and threaded sleeves embracing the opposite end portions of both sections to maintain them in assembled relation, contacts on the opposite ends of the body, and fuse elements electrically connecting the contacts to the sleeves.

7. A double ended fuse plug embodying a pair of identical fuse sections of insulating material positioned in complementary relation and forming a complete fuse body closed at both ends,

- said sections being provided interiorly with circumferential channels adapted to register when the sections are assembled, and a partition peripherally engaging said channels and held in place thereby.
8. A double ended fuse plug embodying a pair of identical fuse sections of insulating material positioned in complementary relation and forming a complete fuse body closed at both ends, said sections being provided interiorly with circumferential channels adapted to register when the sections are assembled, and a partition peripherally engaging said channels and held in place thereby, said partition serving to lock the sections against relative longitudinal movement, and threaded metal sleeves embracing the opposite ends of the sections to hold them in assembled relation.
9. A double ended fuse plug embodying a pair of identical fuse sections of insulating material positioned in complementary relation and forming a complete fuse body closed at both ends, each of said sections having an exterior projection constituting a thread, a metal sleeve screwed on to said threads to secure the sections together, a contact on each end of the fuse body, and a fusible element electrically connecting each contact to the corresponding sleeve.
10. A double ended fuse plug embodying a pair of identical fuse sections of insulating material positioned in complementary relation and forming a complete fuse body closed at both ends, each of said sections having a peripheral channel and an exterior projection constituting a thread, a metal sleeve screwed on to said threads to secure the sections together, a contact on each end of the fuse body, and a fusible element electrically connecting each contact to the corresponding sleeve, the inner ends of the sleeves being flanged into the peripheral channels of the sections to removably secure the sleeves in position thereon.
11. A double ended fuse plug embodying a pair of identical fuse sections of insulating material positioned in complementary relation and forming a complete fuse body closed at both ends, said sections being provided along the joint between them with openings formed collectively in both sections.
12. A double ended fuse plug embodying a pair of identical fuse sections of insulating material positioned in complementary relation and forming a complete fuse body closed at both ends, said sections being provided along the joint between them with an opening through the wall of the body.
13. A double ended fuse plug comprising a pair of complementary semicylindrical sections adapted to be placed in edge abutting relation to form a cylindrical plug body, one end of each of said semicylindrical sections being provided with an integral circular end piece adapted to serve as a closure for the opposite ends of the cylindrical body when said sections are assembled, threaded metallic sleeves embracing the opposite end portions of the cylindrical body to secure said sections together, said sections being provided adjacent one end of each sleeve with a depression, and the wall of the plug body being perforated beneath the sleeves, to permit gases to pass from within the body into the space between the body and the sleeves and out through said depressions.
14. A double ended fuse plug provided intermediate its ends with an enlarged peripheral flange colored to indicate amperage.
15. A reversible fuse plug comprising a pair of identical insulating sections, each section having a tubular semicylindrical wall with an integral semicircular internal partition located medially of the length thereof and having a semicircular hole in the center of the chord edge of said partition, a cylindrical end portion integral with one end of each tubular wall to close the opposite ends of the plug, each of said sections having an opening when said sections are placed in co-relation for the passage of a fuse strip and to serve as a vent, a thread formed on the exterior of each section, metal collars permanently screwed on to said threads to securely clamp the sections together against displacement in all directions, contact points centrally located at the opposite ends of the cylindrical portions, fuse strips attached to said contacts and extending through the interior of the plug to and electrically connected with the metal collars at the corresponding ends of the plug.
16. A double ended fuse plug embodying a pair of L-shaped fuse sections of insulating material positioned in complementary relation and forming a complete fuse body closed at both ends, each of said sections being provided in one end with a slot for the passage of a fusible element, and which slot affords an outlet for explosive gases when said element is fused.
17. A double ended multiple fuse plug having multiple indicating means, there being one indicating means for one end of the fuse plug, and another indicating means for the other end of the fuse plug whereby the opposite ends of the plug are distinguishably marked.
